UNITED STATES PATENT OFFICE.

CHARLES TOOPE, OF NEW YORK, N. Y.

REFRIGERATOR.

SPECIFICATION forming part of Letters Patent No. 285,591, dated December 14, 1880.

Application filed October 21, 1880. (No model.)

To all whom it may concern:

Be it known that I, CHARLES TOOPE, a citizen of the United States, residing at New York, in the county and State of New York, 5 have invented new and useful Improvements in Refrigerators, of which the following is a specification.

This invention relates to refrigerators for general uses; and it consists in the combination 10 of an ice-chamber and a provision-chamber located next to each other, and an air-purifying chamber having a perforated inner wall facing both the ice-chamber and the provision-chamber, so that a current of air circulates 15 from the ice-chamber into and through the purifying-chamber to the provision-chamber. The ice-chamber and provision-chamber are divided from each other by a pan, the inner wall of the purifying-chamber being perforated both above and below such pan. This 20 invention is illustrated in the accompanying drawings, in which—

Figure 1 represents a vertical central section. Fig. 2 is a horizontal section in the line 25 *x x*, Fig. 1.

Similar letters indicate corresponding parts.

The letter A designates the ice-chamber, B the provision-chamber, and C the air-purifying chamber. Access is had to the chambers 30 A B through suitable openings provided with doors D and E, respectively; and the air-purifying chamber C is filled with a composition adapted to absorb odor and moisture—as, for example, a mixture of charcoal and borax.

The letter F designates the inner wall of 35 the air-purifying chamber C, which is also the inner wall of the refrigerator, and G the pan dividing the interior of the refrigerator into the ice-chamber A and provision-chamber 40 B, the first named being above and the other below it. Said inner wall, F, of the air-purifying chamber is perforated both above and below the pan G, as clearly shown in Fig. 1, and the pan is preferably bent or curved 45 downwardly at its edges, where it is secured to the perforated wall, as at I, in order to increase the area of such wall which is exposed to the ice-chamber. Water escapes from the pan G by a drip-pipe, H.

The air, which is admitted to and becomes 50 cooled in the ice-chamber A, passes into the

purifying-chamber C through the perforations above the pan G, and thence into the provision-chamber B through the perforations below the pan, as indicated by arrows in Fig. 1, 55 in which circulation thereof it is freed of impurities, so as to enter the provision-chamber in a pure state.

The outer wall of the air-purifying chamber, constituting also the outer wall of the refrigerator, is made of wood, and is lined with felt or other non-conducting material.

It should be remarked that the chambers A B may be divided from each other by a vertical partition, but I prefer the arrangement shown.

What I claim as new, and desire to secure by Letters Patent, is—

1. The combination, in a refrigerator, of an ice-chamber and a provision-chamber, arranged adjacent to each other, with an air-purifying chamber having a foraminous inner wall, the said purifying-chamber containing a filling which absorbs moisture and odor from the air during its passage from the ice to the provision chamber, substantially as described.

2. In a refrigerator, an air-purifying chamber having an inner perforated wall facing both the ice-chamber and the provision-chamber, said air-purifying chamber containing a composition filling for depriving the air of moisture and odor during its passage from the ice-chamber to the provision-chamber, substantially as described.

3. The combination, in a refrigerator, of an outer casing, an inner foraminous wall, an intervening filling of air-purifying substance, and an upper ice-chamber and a lower provision-chamber divided by a pan which extends from wall to wall of the purifying-chamber, substantially as shown and described, whereby the air is forced to circulate through the air-purifying substance in its passage from the ice-chamber to the provision-chamber, substantially as described.

In testimony whereof I have hereunto set my hand and seal in the presence of two subscribing witnesses.

CHARLES TOOPE. [L. S.]
